UNITED STATES PATENT OFFICE.

BYRON E. WOODCOCK, EUGENE F. MONNIA, AND ALBERT C. REESE, OF SCRANTON, PENNSYLVANIA.

TRAVERSE MECHANISM.

Application filed June 2, 1923. Serial No. 643,019.

To all whom it may concern:

Be it known that we, BYRON E. WOODCOCK, EUGENE F. MONNIA, and ALBERT C. REESE, citizens of the United States, and 5 residents of Scranton, in the county of Lackawanna and State of Pennsylvania, have invented certain new and useful Improvements in Traverse Mechanism, of which the following is a specification.

10 Our present invention relates to improvements in traverse mechanism designed for use in connection with silk winders, spinners and doublers, or other similar and analogous devices.

15 One object of the invention is to provide a simple, economical and durable device for operating the two traverse bars which cooperate with two sets or rows of winding bobbins or spools from a single lever common to both bars, instead of from two separate levers, as has been customary.

Another object is to provide traverse operating mechanism of this character which can be readily shifted or adjusted to produce 20 longer or shorter strokes of both traverse bars.

Still another object is to provide in such a construction, means for readily adjusting the position or stroke of each traverse bar 25 independently of the other.

The invention aims further to provide a construction which may be readily adjusted to give a longer stroke to one traverse bar than the other, whereby longer bobbins can 30 be wound on one side of the machine, and shorter ones on the other.

The invention further aims to provide a construction in which a differential stroke will be given to each traverse bar, or more 40 specifically, an arrangement by which while the length of stroke of each traverse bar will remain the same, its placement or range may be shifted automatically to a slight degree with each successive stroke, thereby avoiding 45 any danger of the threads becoming tangled when being wound or unwound.

With these and other objects in view which will hereinafter appear, the invention includes the novel features of construction 50 and arrangement and combination of parts hereinafter described, and particularly defined in the appended claims.

An embodiment of our invention is illustrated in the accompanying drawings, in 55 which:—

Figure 1 is a plan view of a sufficient por-

tion of a silk winding machine to illustrate our invention, unnecessary parts being omitted, or indicated by broken lines.

Fig. 2 is a detail view of the operating 60 lever and its mounting.

Fig. 3 is a detail view in elevation showing the cam and driving means therefor, the operating lever being omitted for clearness of illustration.

Fig. 4 is a sectional detail through cam and operating parts, taken on a larger scale.

Fig. 5 is a diagrammatic view to illustrate the shift in the wind, and

Fig. 6 is a detail view of the traverse connection.

Fig. 7 is a detail view of bracket 11 on a reduced scale.

Referring by reference characters to these drawings, the numeral 1 designates a portion of the end frame of the machine (at the power end) to the ends of which, the side rails 2 are attached, each of which carries a plurality of brackets 3 corresponding to the number of bobbins on each side of the 65 machine. A horizontal shaft 4, suitably journaled in the bracket bearings beneath these brackets, carries rollers 4^a which are designed to frictionally engage with rollers 5^a on the ends of the bobbins 5 and rotate 85 the same by frictional engagement therewith, the brackets being provided with recesses 3^b into which the spindle ends 5^b may be dropped, the recesses being of such depth as to allow the rollers 5^a of the bobbins to 90 come in contact and be supported by the periphery of the rollers or friction discs 4^a.

Other slots of less depth are provided, as indicated at 3^c, into which the ends of the bobbin shafts may be seated when it is desired to stop any one bobbin without stopping the operation of the entire machine. The horizontal shafts 4 are driven from shaft 6 through the intermediary of spiral gears 7 and 8, shaft 6 being driven from any suitable source of power in the customary or any desired manner. Associated with each row of bobbins or spools is a traverse bar 9 which carries a plurality of thread guides 9^a of the usual or any desired form. The parts thus far described are such as are customary in winding machines of this character.

For operating the two traverse bars on opposite sides of the machine, we provide a lever 10, of the first order, fulcrumed at 10^a upon a bracket 11 fixed in vertical center line of end member 1 of the machine. Preferably

bracket 11 is secured to the frame by bolts passing through vertically elongated slots in the end frame (Fig. 7) which enables the lever to be accurately positioned vertically 5 during erection. The said lever 10 is preferably so fulcrumed as to be capable of lengthwise adjustment for the purpose of giving a longer throw to the traverse bar on one side of the machine than on the 10 other, as will hereinafter more fully appear. The preferred manner of securing an adjustable fulcrum is illustrated in the drawings, in which it will be seen that the bar 10 has an enlarged or hub portion 10^b which 15 rests upon the upper face of the bracket 11, and hub 10^b having a vertical cylindrical passage through which passes the stud bolt 12, the lower end of which has a reduced portion which passes through an elongated 20 opening 11^a in the bracket and is locked in position therein by a securing nut 11^b threaded on the lower end of the stud bolt.

Preferably we use the stud bolt as a support for a spring to exert pressure on 25 the lever, tending to rock it normally in one direction, and in the preferred embodiment of our invention shown in the drawings, this is accomplished by providing a torsion coil spring 13 encircling the portion of the 30 stud bolt which is projected above the surface of the lever 10 for this purpose, the end 13^a of the spring being connected with the lever, and the other end being connected with a collar 14 which is locked to the upper 35 end of the stud by a locking set screw 14^a. It is obvious that by loosening the set screw and turning the collar by the use of any suitable tool cooperating with kerfs or the like in the collar, the spring may be ad- 40 justed to any desired tension.

The lever is rocked by the spring in one direction to secure corresponding movement of the traverse bars connected to the ends of the lever, movement in the reverse direction being effected by a cam 15 which is driven from the shaft 6 through mechanism hereinafter described, this cam cooperating with a roller 16 carried by a bracket 17 adjustably secured to the lever by a locking bolt 17^a working in a slot 10^c in the lever 10. As this cam rotates, through its cooperation 45 with the roller 16, which is held in contact therewith by the spring 13 above described, the lever is rocked on its fulcrum and hence 50 the traverse bars are reciprocated, as will be evident.

It is desirable that the cam 15 have a differential action so that on each successive stroke the placement or range of the 55 traverse bars and thread guides will be slightly shifted though the length of stroke will always remain the same, and the thread guides will be stopped at the ends of their movement at different points relative to the ends of the bobbin. This prevents tangling

of the threads when the thread is rapidly unwound from these same bobbins when they are placed on the next machine in the process of spinning, doubling, etc. This we accomplish by the mechanism which will 70 now be described.

A bracket 18 is adjustably connected to the end frame member 1 preferably by means of bolts 18' passing through the bracket member and through elongated slots 75 in the frame member. The bracket has an offset end or portion 18^a to which is secured a stud 19 conveniently by forming the stud with a threaded end which projects through an opening in the bracket, the stud having 80 a thrust receiving shoulder or collar 19^a on one side of the bracket arm, and a clamping nut 19^b on the other side with preferably an interposed washer.

A worm wheel 20 is rotatably mounted on 85 this stud being retained thereon by a collar portion 19^c resting in a recess within the body of the wheel, and this worm gear meshes with a worm 6^a on the shaft 6. Stud member 19 has a stud extension 19^d which 90 is eccentrically positioned relative to the stud portion 19 and on this stud portion 19^d is journaled a bushing or sleeve 21. The inner end of the sleeve has fixed thereon, or integral therewith, a gear 21^a which meshes 95 with an internal gear 20^a carried by, or formed integral with the worm wheel 20. The bushing or sleeve 21 carries at its outer end a sleeve or hub member 15^a of the cam 15 which is rigidly secured thereto. 100

The inner face of the gear 21^a is formed inclined to a plane perpendicular to the axis of the gear, this inclined face in effect constituting a cam surface indicated at *a* which cooperates with a raised portion or 105 projection *a'* on the adjacent face of the worm wheel or gear 20.

It will thus be apparent that as the worm wheel 20 is rotated the gear 21^a will be rotated by the internal gear 20^a which will 110 rotate the cam 15 and impart the hereinbefore described movement to the lever 10 and traverse bars. The spur gear 21^a has less teeth (preferably 7 less) than the internal gear 20^a, consequently it rotates 115 slightly faster than the internal gear and the worm wheel 20 which are integral, and this difference in relative speeds causes the round knob *a'* to travel around the cam surface *a*, giving the axial movement to the part 21 carrying the cam. The essential part of the 120 design to produce the differential motion is to have two gears with a different number of teeth meshing into each other to produce different speeds of rotation. By reason of 125 the adjustable connection of the bracket 18 to the frame, and the adjustable connection of the roller 16 to the bar 10, it will be seen that the gear assembly above described, can be moved towards or from the fulcrum 130

of the lever 10 to thus produce a longer bobbin and traverse mechanism therefor, or shorter stroke of the traverse bars. It will be obvious that this adjustment can be readily effected, and that whatever the adjustment, the relative stroke of the traverse bars will be unchanged, the relative stroke being adjusted when desired, by shifting the fulcrum of the lever 10 as above described.

The sleeve 21 is held in position on the 10 stud portion, or shaft projection 19^d with the cam face *a* of the spur gear 21^a yieldingly pressed against the projection or raised portion *a'* by a helical spring 22, which bears at its inner end against the end 15 of the sleeve, and at its outer end against a plate or washer 23, which is held in position by a bolt 24 which extends through the spring and has its inner end tapped into the end of the stud or shaft projection 19^d.

20 The traverse bars 9 are connected to the respective ends of the lever by connecting links 25 and the connection of the link with the lever 10 is preferably made adjustable lengthwise of the operating lever, whereby 25 the length of stroke of the traverse bar may be adjusted. The preferred manner of effecting this adjustment is shown in the drawings, in which each end of the lever 10 is provided with a pair of projecting lugs 10^d 30 through which pass an adjusting screw 27 which carries a bracket 28 to which the end of the link 25 is pivotally connected.

The link 25 is also adjustably connected to the traverse bar 9 in the customary 35 manner.

Having thus described our invention, what we claim is:—

1. In apparatus of the class described, the combination with a row of winding 40 spools and a cooperating traverse bar, of a lever fulcrumed on a normally fixed pivot and connected with said traverse bar, a cam located to one side of the pivot of said lever and cooperating with said lever to actuate 45 the same, and means for adjusting said cam lengthwise of said lever.

2. In apparatus of the class described, the combination with two rows of winding 50 devices and a traverse bar associated with each row, of an actuating lever of the first order having its ends connected with said traverse bars, a fulcrum for said lever, means for effecting adjustment of said fulcrum lengthwise of said lever, and means 55 for operating said lever.

3. In apparatus of the class described, the combination with a winding spool or bobbin, of a traverse device, and means for imparting a rectilinear reciprocating motion 60 to said traverse mechanism, including means for shifting the placement of said traverse mechanism without altering the length of stroke thereof.

4. In apparatus of the class described, the combination with a winding spool or

bobbin and traverse mechanism therefor, of a cam for actuating said traverse mechanism, and means for automatically and continuously altering bodily the position of said cam.

70

5. In apparatus of the class described, a traverse bar, a lever fulcrumed at a fixed point and having a free end connected with said traverse bar, a cam arranged to coat with an intermediate portion of said lever 75 to operate the same, means for continuously bodily shifting said cam, and means for rotating said cam.

6. In apparatus of the class described, a traverse actuating lever, spring means tending to move the same in one direction, a cam for moving said lever against the tension of the spring, and means for automatically and continually moving said cam 80 bodily.

7. In apparatus of the class described, the combination of a winding spindle, strand guiding means having a movement with respect to said spindle to form superposed windings thereon, and means for operating 90 said strand guiding means comprising a driving member journaled on a fixed axis and including an internal gear, a spur gear journaled in eccentric relation to said driving member, and meshing with said internal 95 gear, said spur gear having a cam face, and said driving member a raised cam contact portion cooperating therewith, a helical cam connected with said spur gear to be operated thereby, and a cam contact element 100 engaging said helical cam and operatively connected with said strand guiding means.

8. In apparatus of the class described, the combination of a winding spindle, strand guiding means having a movement with respect to said spindle to form superposed windings thereon, and means for operating 105 said strand guiding means comprising a bearing stud, a driving member journaled on said stud including an internal gear, said 110 stud having an eccentrically located shaft projection, a spur gear journaled on said shaft projection and meshing with said internal gear, said spur gear having a cam face coacting with a cam contact part on said driving member, a helical cam connected with said spur gear to be operated 115 thereby, and means whereby movement of said cam actuates said strand guiding means.

9. In apparatus of the class described, a lever articulated upon a fixed pivot, a helical cam rotating about an axis substantially perpendicular to said lever and coacting therewith to operate the same, means for rotating said cam, means for automatically imparting axial movement to said cam, and means for varying the position of the cam 120 lengthwise of said lever.

10. In apparatus of the class described, a 130

- lever fulcrumed upon a fixed axis, a bearing stud, a support therefor, a driving wheel journaled on said stud, an internal gear carried by said driving wheel, said stud 5 having an eccentrically located shaft projection, a spur gear journaled on said shaft projection and meshing with said internal gear, said spur gear having a cam face coacting with a raised portion on said driving 10 wheel, and a helical cam connected with said spur gear to be operated thereby and coacting with said lever.
11. In apparatus of the class described, a supporting frame, a lever pivotally supported thereby, a bracket adjustably carried by said frame, a bearing stud carried by said bracket, a driving wheel journaled on said stud and carrying an internal gear at one side, said stud having an eccentrically 15 located shaft projection, a sleeve journaled on said shaft projection and having a spur gear at one end meshing with said internal gear, said spur gear having a cam face coacting with a raised portion on the adjacent 20 face of said driving wheel, and a helical cam carried by said sleeve and coacting with said lever.
12. In apparatus of the class described, the combination with a spool driving shaft 30 having a worm thereon, of a worm wheel meshing with said worm, a bearing stud on which said worm wheel is journaled, said worm wheel having a concentrically arranged internal gear projecting from one 35 face thereof, and said bearing stud having an eccentrically located shaft projection, a spur gear journaled on said shaft projection, and having a face coacting with the adjacent face of said worm wheel, one of said faces 40 being formed as a cam and the other having a projecting part coacting therewith, a helical cam operatively connected with said gear, and a traverse operating lever coacting with said cam.
- 45 13. In apparatus of the class described, the combination with a spool driving shaft having a worm thereon, of a worm wheel meshing with said worm, a bearing stud on which said worm wheel is journaled, 50 means for adjusting said stud in a direction perpendicular to its axis, said worm wheel having a concentrically arranged internal gear projecting from one face thereof and said bearing stud having an eccentrically 55 located shaft projection, a spur gear journaled on said shaft projection and having a face coacting with the adjacent face of said worm wheel, one of said faces being formed as a cam and the other having a projecting 60 part coacting therewith, a helical cam operatively connected with said gear, a traverse operating lever disposed adjacent said helical cam, and a cam contacting element 65 carried by said lever and adjustable lengthwise thereof.
14. In apparatus of the class described, the combination with a spool driving shaft having a worm thereon, of a worm wheel meshing with said worm, a bearing stud on which said worm wheel is journaled, said 70 worm wheel having a concentrically arranged internal gear projecting from one face thereof, and said bearing stud having an eccentrically located shaft projection, a sleeve journaled on said shaft projection having a spur gear at one end meshing with said internal gear, and a cam face coacting with a projected portion on the face of said worm wheel, a spring carried by said shaft projection tending to force said sleeve and 75 spur gear towards the worm wheel face, a helical cam carried by said sleeve, and a traverse operating lever having a part co-operating with said cam.
15. In apparatus of the class described, the combination with a spool driving shaft having a worm thereon of a worm wheel meshing with said worm, a bearing stud on which said worm wheel is journaled, said worm wheel having a concentrically arranged internal gear projecting from one 80 face thereof, and said bearing stud having an eccentrically located shaft projection, a sleeve journaled on said shaft projection having a spur gear at one end meshing with said internal gear, and a cam face coacting with a projected portion on the said worm wheel, a spring carried by said shaft projection tending to force said sleeve and spur 85 gear towards the worm wheel face, a helical cam carried by said sleeve, and a traverse operating lever having a part co-operating with said cam.
16. In apparatus of the class described, the combination with two rows of winding spools and cooperating traverse bars, of a single lever having a central fulcrum, means connecting the ends of said lever with said traverse bars, said means being capable of adjustment lengthwise of said lever, and cam means for actuating said lever.
17. In apparatus of the class described, the combination with two rows of winding spools and cooperating traverse bars, of a single lever having a central fulcrum, means connecting the ends of said lever with said traverse bars, said means being capable of adjustment lengthwise of said lever, and cam means for actuating said lever, said cam means being also capable of adjustment lengthwise of said lever.
18. In apparatus of the class described, the combination with two rows of winding spools and cooperating traverse bars, of a single lever having a central fulcrum, means connecting the ends of said lever with said traverse bars, said means being capable of adjustment lengthwise of said lever, cam 125

means for actuating said lever, said cam means being also capable of adjustment lengthwise of said lever, and means for shifting the fulcrum of said lever lengthwise thereof.

19. In a silk winding machine having two rows of winding spindles and cooperating traverse bars, a single actuating lever disposed in the same plane with said traverse bars, and having its central portion fulcrumed on a normally fixed pivot, and an actuating cam means cooperating with said lever at a point between its pivot and one of the traverse bars.

20. In apparatus of the class described, 15 the combination with two rows of winding spools and cooperating traverse bars and means for imparting a rectilinear movement to said traverse bars, including means for altering the length of stroke of each traverse bar independently of the other without shifting the placement of either traverse bar.

In testimony whereof we affix our signatures.
